UNITED STATES PATENT OFFICE.

WILLIAM DUBILIER, OF NEW ROCHELLE, NEW YORK, ASSIGNOR TO DUBILIER CONDENSER CORPORATION, OF NEW YORK, N. Y., A CORPORATION OF DELAWARE.

RADIO APPLIANCE.

Application filed December 15, 1924. Serial No. 756,081.

My invention relates to improvements in radio appliances; and particularly to a device for uniting in a single self contained structure at least two of the electrical units that are employed with radio apparatus now in general use; with the result that a suitable saving of space is effected, and the conductors that unite the parts of radio apparatus can be disposed to better advantage.

10 The nature and objects of the invention are fully set forth in the following description taken with the accompanying drawings upon which two or more preferred embodiments of the principle of my invention are illustrated. I do not, however, wish to be limited to the exact constructions shown herein, as I may vary the details within the limits defined by the broad and general meanings of the terms of the appended claims:

20 On the drawings, Figure 1 is a vertical sectional view of a construction according to the principle of my invention;

25 Figure 2 is a similar sectional view of another form of my invention;

Figure 3 is an upper end or top plan view of part of the construction appearing in Figure 1; and

30 Figure 4 is a sectional view taken on the line 4—4 of Figure 2 looking upward, as indicated by the points of the arrows.

The same numerals identify the same parts throughout.

Referring first to Figure 1, I show at 1 a base of some suitable substance such as insulation, having a central bore or passage 2 through it; the base being provided at its lower end with a flange 3 upon which it may rest and be conveniently secured in position.

40 This base also serves as a support for a housing sleeve or socket 4 having a bore or passage 5 through it from end to end, with an internal rib 6 providing a shoulder 7 to be engaged by the end of a thermionic valve or vacuum tube

45 8. This tube may be of the usual type comprising an evacuated vessel of glass, the extremity of which is encircled by a band or ferrule 9 which can be inserted into the upper end of the sleeve or socket 1 and rest upon the

50 shoulder 7. This shoulder or abutment prevents distortion of the contact springs 15 in the event that the tube 8 is carelessly inserted. The tube 8 will contain the plate, grid and filament ordinarily present in such units, and the

three electrodes named will be united to conductors which pass through the end of the tube and are joined to the outside pillars or contact studs P and G which will be united to the plate and grid respectively, and two additional pillars or contact studs F+ and F- which will be connected to the two opposite terminals of the filament.

Enclosed by the housing sleeve 4 below the internal rib 6 will be a pair of windings 10 and 11 constituting the primary and secondary respectively of a transformer. These windings may be embedded in wax 12 or some other suitable substance, and the bottom or lower end of the socket 4, within the support or base 1, may be provided with a shoulder 13 to receive 70 a cover 14 removably held in place in any suitable manner.

To enable the tube to be connected in the circuit of the radio apparatus which, for example, may be a well-known radio receiving set, I attach to the inside of the sleeve 4, a number of spring contacts 15 to co-operate with the contacts of the tube 8. The base 1 and sleeve 4 may have any desired cross-sectional shape, but as indicated in Figure 3, the sleeve 80 4 is cylindrical; and the contacts 15 will preferably be in the form of leaf springs secured against the surface of the bore 5 below the rib 6 and having portions which project toward the center in position to press against 85 the ends of the contact studs F+ and F-, G and P. This feature is indicated in Figure 3 which shows the socket in top plan with the tube removed, the position of the contact studs at the bottom of the tube engaging the 90 spring contacts 15, being indicated in dotted lines in Figure 3. Each of the leaf springs 15 is made fast to a contact segment 16 secured upon the outside of the sleeve 4, these segments being of conductive material preferably spaced equi-distantly apart and to some extent embedded in the material of which the socket 4 is composed. The springs 15 and socket 16 may be united by screws 17 and to enable the base 1 to receive the socket, 95 the upper end of the bore 2 may be enlarged, if desired, as shown at 18 to provide a shoulder 19. Then when the socket 4 is inserted into the upper end of the base 1, the projecting segments 16 will rest upon the shoulder 19. 100 Instead of enlarging the upper end of the bore 2 all the way around the circumference thereof, I may cut slots into the walls of this

105

bore from the upper end of the sleeve, wide enough to receive the segments 16, these segments engaging the inner ends of the slots the same as they are shown engaging the shoulder 19 in Figure 1. To hold the sleeve 4 in place, threaded bores may be fashioned in the sides of the base 1 to receive threaded screws 20 which can be turned in to press against the segments 16, and held tight by binding nuts 21. The tube 8 may have the shell or band 9 provided with a projection not shown, to engage a bayonet slot in the upper end of the socket 4, this bayonet slot being also not shown, as it is quite familiar to those skilled in the art, and almost every tube is provided with such means to enable it to be held in the socket receiving it. When the tube is inserted into the upper end of the socket 4 and caused to abut the shoulder 7, it is made to assume such position that each of its four contact studs engages one of the leaf springs 15, and the socket 4 is secured against movement in the base 1 by the engagement of the screws or bolts 20 with the segments or contacts 16. Any suitable means may be provided to enable connection to be made through the base 1 and through the socket 4 with the terminals of the transformer windings 10 and 11. I illustrate connections for the transformer windings fully in Figures 3 and 4 which are presently to be described. The advantage of a device of this sort combining in a single structure both a vacuum tube and a transformer is that with radio receiving sets utilizing one or more stages of amplification, the vacuum tube amplifier and the amplifying transformer can be housed together in a single structure saving a good deal of space, and enabling the conductors which unite the various parts of the set to be disposed to much greater advantage and with more convenience, inside of the casing or cabinet which encloses the radio receiving set.

Figures 2 and 4 illustrate the principle of my invention as practiced with a base or support only, enabling me to dispense with the socket 4. The base is indicated at 22 with a chamber 23 therein and having a flange 24 at its lower end. From the top 25 of the base extends a neck 26 having a passage 5^a therethrough to communicate with the chamber 23, this passage containing a shoulder 27 similar to the shoulder 7, so that the vacuum tube 8 can rest upon it. Through the sides of the base pass screws 28 constituting binding posts carrying nuts 29 to hold the screws in place and secure thereto the extremities of electrical conductors. The heads of these screws are on the inside of the compartment 23 and they serve to hold in place leaf springs 30 providing contacts similar to the leaf springs 15 above-mentioned for the contact studs of the tube 8. Within the compartment 23 are transformer windings 10 and 11 as before, em-

bedded in wax or the like 12 and the base 22 again has an internal shoulder 13 against which is secured a cover 14.

As indicated in Figure 4, the binding screws 28 may be seven in number, four of which are associated with the leaf spring contacts 30, while two others are united to the extremities of the primary winding 10. The secondary winding 11 may have one extremity secured to one of the spring contacts 30, 75 the opposite extremity being joined to the seventh or remaining binding post 28. As is understood when an amplifying transformer is employed in a radio receiving set, between two vacuum tubes, the primary of the transformer is connected in the output circuit of the one tube, and the secondary is joined to the input circuit of the other. Hence, in connecting one terminal of the secondary winding 11 to one of the spring contacts 30, it is 80 desirable to select the spring 30 which will ordinarily be in circuit with the grid of the tube 8, the connections of an amplifying radio receiving set being made in this way. The other terminal of the secondary 11 may be 85 united to the binding post to which is affixed the spring 30 which will engage with the stud leading to the negative terminal of the filament, and for this purpose, I may employ a conducting strip 31 having recesses 32 in its 90 ends, this strip being curved to fit against the side of the base 22, the notches receiving the screws or contacts 28, and the nuts 29 holding the conductor strip in place. This conductor strip may be discarded in case it is not desired 95 to connect the other terminal of the secondary directly to the negative end of the filament in the tube 8. The upper end of the neck 26 may have an L-shaped or bayonet slot 33 there- 100 in, and the band 9 of the tube 8 may have a pin 34 to engage this slot, the same as described above in connection with the form of my invention of Figures 1 and 3.

The device shown in Figures 3 and 4 enables a vacuum tube and a transformer for 110 amplifying or for any other purpose, to be combined very well in a single structure in such a manner that the tube can be inserted and withdrawn with the same ease as permitted by ordinary sockets heretofore employed, 115 and with the transformer in the base or support 22 provided with connections to binding posts mounted in this base so that it can be connected very conveniently in the circuit of a radio receiving set, and the necessity for 120 setting up the tube at one point in the radio set, and the transformer at another point is obviated. In view of the fact that practically all sets have several stages of amplification, the merit of the invention can be appreciated, 125 because the ordinary radio receiving set generally presents to the eye of the observer, a maze or network of connectors, with the transformers, the tubes and the other parts grouped together as closely as possible, so 130

that the assembling of such a set is very difficult, not only because of the need for putting the various appliances each in its own separate position, but also because the various connections must be properly made. With this invention, the work of assembling a receiving set is greatly simplified, because the transformers, and the tubes can be handled together, and the work of connecting up the various parts is thus very much diminished.

The device of Figures 2 and 4 is somewhat simpler than that of Figures 1 and 3 because in Figure 1, for example, the member 4 which receives both the tube and transformer, is used in conjunction with a separate base or support 1; while in the construction of Figure 2, for example, the support 1 by itself constitutes the member for housing the transformer and providing the socket for the tube 8.

In the device shown in Figure 2, I may also employ a partition 35 above the transformer, the wax 12 being confined between this partition and the closure 14, leaving a space in the upper part of this member 1 for the spring terminals 30 and providing room for the movement of these terminals as required when the tube is inserted in the socket 26.

It is of course to be understood that my invention is not limited to the inclusion in the members 1 and 4 of a transformer for amplifying only, but covers in the combination specified, a transformer for any purpose required.

Having described my invention, what I believe to be new and desire to secure and protect by Letters Patent of the United States is:—

1. The combination of a base, a housing sleeve in said base, one end of said housing sleeve adapted to provide a socket for a vacuum tube and the other end to receive a transformer, a closure for the transformer carried by said sleeve, spring contacts in said sleeve to engage the terminals of the tube, contact segments on the outside of said sleeve connected to said spring terminals, and binding screws mounted in the base to engage said segments and hold the sleeve in position.

2. A member in the form of a base having a chamber therein, and a socket projecting from the top thereof to receive a vacuum tube, spring terminals in said chamber to engage the terminals of the tube, binding screws holding said terminals in place and projecting to the outside of said member, a transformer in said chamber and binding screws projecting to the outside of said member to connect with the terminals of the transformer, together with a connecting strip to unite one of the binding screws for the transformer to one of the binding screws for the spring terminals, to connect with the vacuum tube.

Signed at New York in the county of New York and State of New York this 13th day of December, A. D. 1924.

WILLIAM DUBILIER.
